UNITED STATES PATENT OFFICE.

JOSEPH A. BUNNELL, OF NEW YORK, N. Y.

CUTTING OR SEVERING DEVICE.

SPECIFICATION forming part of Letters Patent No. 355,136, dated December 28, 1886.

Application filed July 23, 1885. Serial No. 172,478. (No model.)

To all whom it may concern:

Be it known that I, JOSEPH A. BUNNELL, a citizen of the United States, residing at New York, in the county and State of New York, 5 have invented new and useful Improvements in Cutting and Severing Devices, of which the following is a specification.

This invention relates to devices or apparatus for cutting or severing; and the nature 10 and object of this invention are to enable the cutting or severing to be rapidly and easily performed.

This invention is illustrated in the accompanying drawings, in which Figure 1 is a front 15 view of the cutting or severing device. Fig. 2 is a section in the plane $x x$, Fig. 1. Fig. 3 is a front view on a larger scale than Fig. 1. Fig. 4 is a plan view of the cutting or severing device. Fig. 5 is a section in the plane $y y$, 20 Fig. 4. Fig. 6 is a detail view of the presser rod or arm and its adjacent parts.

Similar letters indicate corresponding parts.

In the drawings, the letter A designates a supporting-frame. The supporting-frame A 25 may rest upon a table, C, or other suitable base. The frame A supports two arms, A³, carrying a ledger-blade, A⁴. The arms A³ support a guide, H, which in the example shown in the drawings consists of a rod. Along this 30 guide travels the cutter-carrier H'. The cutter-carrier H' is shown as being provided with a perforation, through which the guide H passes, and the cutter-carrier H' rests loosely on the guide H, so that the carrier H' can 35 easily move back and forth.

The cutter or severing device H² of the drawings is a rotary severing device. The shaft h of the severing device H² rests in the carrier H', said carrier H' having a perforation or recess for the reception of the shaft h. The severing device or cutter H² can be held to the shaft h by a nut, h', so as to leave the cutter H² free to rotate. The cutter H² can be rotated 40 by a pulley, h², with which pulley engages a cord, strap, or chain, h³. The cord, rope, or chain h³ is secured at each end to arms A⁶ or to other convenient parts of the device. The rope or chain h³ also passes around guide-pulleys h⁴, which are mounted on studs h⁵, or other 45 convenient parts of the carrier H'. A presser-rod, h⁶, forces the cutter H² into contact with the ledger-blade A⁴. The presser-rod h⁶ passes

through bearings h⁷ and h⁸, which bearings are formed or rest upon an arm, H³. This arm H³ is secured to the carrier H'. The presser-rod 55 h⁶ is provided with a roller, h⁹. This roller h⁹ rests against an abutment, A⁷. The abutment A⁷ is shown as being formed by a rod, along which the roller h⁹ can travel when the cutter moves back and forth.

The presser-rod h⁶ is provided with a sleeve or abutment, h¹⁰, and between this sleeve or abutment and the bearing h⁸ is a spring, h¹². A coiled spring surrounding the presser-rod h⁶ will answer, the spring h¹² being so applied 65 as to force the carrier H' into such a position that the cutter H² will be in contact with the ledger-blade A⁴. In case the ledger-blade A⁴ should not have an even surface, the yielding of the spring h¹² will allow the cutter H² in its 70 movement to yield to any irregularity in such surface of the ledger-blade A⁴, while at the same time the cutter H² will be continually in contact with the ledger-blade A⁴.

The sleeve or abutment h¹⁰ may be adjustable on the rod h⁶, so as to vary the tension of the spring h¹². A screw, h¹³, is caused to bear against the shaft h, and as the cutter H² is worn away the screw h¹³ can be caused to press the shaft h and cutter H² nearer to the ledger-blade A⁴, thus compensating for wear.

The shaft h is provided with slots or grooves h¹⁴, into which slots or grooves h¹⁴ enter screws h¹⁵. The portions of the screws h¹⁵ which enter the slots or grooves h¹⁴ are of such size as 85 not to occupy the entire width of the slots h¹⁴, thus allowing the shaft h, and with it the cutter H², to rock within narrow limits. This rocking or tipping is caused by the actuating-lever H⁵, which imparts motion to the cutter-carrier H' by means of the connecting-rods H⁶ H⁸. The connecting-rod H⁸ is connected with a stud or screw, h¹⁶, secured to the shaft h, said stud h¹⁶ passing through a slot or hole, h¹⁷, in the carrier H'. The slot or hole h¹⁷ is of 95 such a size as to allow the stud h¹⁶ some motion in said slot h¹⁷, thus enabling the shaft h to be rocked. As the rod H⁸ is caused to move the cutter H² back and forth, the rod H⁸ at the same time slightly inclines or tilts the cutter 90 H² to one side or the other against the ledger-blade A⁴. This inclined position of the cutter H² secures a shearing operation as the cutter H² moves along the ledger-blade A⁴, and insures 100

a perfect severing of any material that is inserted between the ledger-blade A⁴ and the cutter H²—as, for example, paper, cloth, and the like.

5 A sponge, h¹⁸, or its equivalent, can be secured to a small arm, h¹⁹, which arm h¹⁹ can be secured to the shaft h. The sponge h¹⁸ will serve to remove paste, moisture, or foreign matter adhering to the edge of the cutter H², which is liable to be the case when the cutter H² is caused to act on material having paste or moisture.

When the cutter H² is caused to move rapidly, it may occur that paste, moisture, or foreign matter—as, for example, particles of the material being severed—will lodge or be thrown against the guide-pulleys h⁴. To prevent this I cover or partly cover the guide-pulleys with shields or guards a a. These shields or guards a a may be formed of sheet metal or other suitable material, and screwed or otherwise secured to the carrier H' in such a manner as to cover or partly cover the guide-pulleys h⁴. (See Figs. 3 and 4.) In Fig. 3 one of said shields or guards a a is removed, so as to expose a guide-pulley, h⁴, while another shield or guard, a, is shown in position with a guide-pulley underneath. (Indicated in dotted lines.)

30 To secure an easy movement of the carrier H' along the guide H, the carrier H' can be provided with rollers c c. These rollers c c can be made to support the carrier H', and said rollers c c will permit of an easy movement of the carrier H' along the guide H. The rollers c c may have their shafts or bearings in arms or lugs secured to the carrier H'; or the rollers may be mounted in any suitable way on the carrier H'. When the carrier H' travels rapidly back and forth, the blow or jar produced by the carrier H' coming into contact with the frame or arms A³ can produce injury. To avoid or deaden such blow or jar, a yielding surface or a buffer or spring, b b, can be placed between the carrier H' and the arms A³. This yielding surface may be formed, for example, by coiled springs placed about the guide H', or by felt, rubber, or yielding material, which rubber, felt, or yielding material may be attached to the arms A³, or to the carrier H'; or tubes of rubber, felt, or other yielding material may be placed about the guide H, between the carrier H' and the arms A³. When the carrier H' comes into sudden contact with the yielding surface b b, the yielding surface will gradually retard the movement of the carrier H' and avoid a blow or jar, which might be caused by abrupt stoppage of the carrier H'.

60 The cutter is shown as being adapted to be moved by a treadle. The treadle shown in the drawings contains two pedals, D D, swinging about pivots E E. The pedals are provided with arms F F, which connect with arms A² A². The arms A² A² are firmly connected to or form part of the actuating lever or arm H⁵, swinging about a pivot or fulcrum, A⁵.

By depressing one of the pedals D of the treadle the actuating lever or arm H⁵ is caused to swing or move in one direction, and by depressing the other pedal the lever H⁵ is caused to swing in the opposite direction. The actuating lever or arm can thus be caused to move back and forth by depressing first one and then the other of the pedals D D of the treadle. As the arms F F swing with the arms A² A², the pedals D D will alternately rise and fall as the arms A² A² oscillate. The actuating lever or arm is pivoted or suitably connected to a connecting-rod, H⁶. The connecting-rod H⁶ is pivoted or suitably connected to a lever or connecting arm, H⁷, swinging about a pivot or fulcrum, G. The lever or arm H⁷ is pivoted or suitably connected to the rod or arm H⁸, which, as already described, is connected with the cutter H². The back-and-forth motions of the actuating-lever H⁵ cause back-and-forth motions of the rods and levers H⁶ H⁷ H⁸, and of the cutter H². The cutting operation can thus be rapidly performed without it being necessary for the operator of the machine to use the hands in the cutting operation. The hands of the operator are thus left free to perform other work, as required.

The cutting device above described will be found very useful, for example, in machines or apparatus in which one or more strips of paper or suitable material, B, are led over pasting apparatus and to a box or cover, for the purpose of being applied to such box or cover. In such machine or apparatus such cutting device can be used to cut or sever proper lengths from the strip or strips B, which strip or strips B can be fed between the ledger-blade A⁴ and the cutter H², as seen in Fig. 5. As the cutting or severing operation can be attained by the action of the feet upon the treadle D D, the hands of the operator are free to properly adjust and apply the strip or strips B to a box or cover, or to do other work, as may be required. Of course I do not limit myself to the application of the cutting or severing device to box-machines, as said cutting or severing device may be advantageously applied elsewhere than in box-machines—as, for example, in wrapping-machines, for cutting proper lengths of wrappers, or in various other machines or apparatus where cutting or severing is to be done.

It will be noticed that by depressing one of the pedals D D of the treadle the cutter H² will travel along to one end of the ledger-blade A⁴, or to one side of the apparatus, and will remain there until the other of said pedals D D is depressed, when the cutter H² will travel to the other end of the ledger-blade A⁴, or to the opposite side of the apparatus, and will then remain there until the first-named pedal is again depressed. The treadle thus positively moves the cutter H² both back and forth, and the use of a spring or weight for moving the cutter is dispensed with. A disadvantage of having a cutter moved positively in one direction by a treadle and returned to its original

position by a spring or weight is, that when the cutter has been moved by the treadle against the action of the spring or weight into a certain position the cutter will be returned 5 at improper periods to its original position by the spring or weight, unless held by a suitable retaining device or by the pressure of the foot upon the treadle until such time as it is proper for the cutter to return to its original position.

10 As the spring or weight may impart motion to the cutter at improper periods, and as such motion of the cutter is accompanied by a cutting or severing of the material which is being acted upon by the cutter, the progress and 15 quality of the work may be injuriously affected by the motion of the cutter at improper periods.

15 In my device springs or weights for moving the cutter are dispensed with. The treadle 20 positively moves the cutter both back and forth, and the cutter remains at rest until the operator desires the cutter to move, when such operator presses upon the proper pedal of the treadle, and thus causes the cutter to move.

25 I am aware that cutting or severing devices are set forth or described, for example, in United States Letters Patent No. 67,669, dated August 13, 1867, and No. 294,486, dated March 4, 1884, and No. 299,225, dated May 27, 1884.

30 I am also aware that it is not new to cause a cutting device to move in one direction by a pedal, a spring being employed to return the

cutter to its original position, such arrangement being set forth in United States Letters Patent No. 278,442, dated May 29, 1883. Such 35 prior known devices I do not claim.

What I claim as new, and desire to secure by Letters Patent, is—

1. The combination, with a cutter or severing device, H², a carrier, H', and a guide, H, of an actuating lever or arm, H⁵, connecting mechanism, substantially as described, between the arm H⁵ and the carrier H', and a treadle, D D, for positively moving said arm in opposite directions, substantially as set 45 forth.

2. The combination, with a cutter or severing device, H², a carrier, H', and a guide, H, of the swinging lever or arm H⁵, pivoted at its lower portion and having oppositely-projecting rigid arms, A² A², the pivoted pedals D D, connected, respectively, with the rigid arms, the swinging vertical rod H⁷, connected with the carrier, and the rod H⁶, connecting the swinging vertical rod with the upper end of 55 the lever or arm, substantially as described.

In testimony whereof I have hereunto set my hand and seal in the presence of two subscribing witnesses.
